**SCUFFING TOOL FOR REPAIRING SEWN-IN
BICYCLE TUBE TIRES OR THE LIKE**

Philip Quartararo, 2309 Avenue Y, Brooklyn, N.Y.

Filed June 3, 1964, Ser. No. 80,257

Term of patent 3½ years

(Cl. D54—13)

FIG. 1

FIG. 2

FIG. 3

FIG. 1 is a side elevational view of a scuffing tool for repairing sewn-in bicycle tube tires or the like embodying my new design, the opposite side being similar;

FIG. 2 is a front elevational view thereof;

FIG. 3 is a bottom plan view thereof; and

FIG. 4 is a top plan view thereof.

I claim:

The ornamental design for a scuffing tool for repairing sewn-in bicycle tube tires or the like, as shown.
